UNITED STATES PATENT OFFICE

157,366

FLOWER SUPPORT

Ruth Gerth, San Francisco, Calif.

Application May 29, 1948, Serial No. 146,684

Term of patent 7 years

(Cl. D35—3)

To all whom it may concern:

Be it known that I, Ruth Gerth, also known as Ruth Gerth Kosmak, a citizen of the United States of America, residing in the city and county of San Francisco, and State of California, have invented a new, original, and ornamental Design for a Flower Support, of which the following is a specification, reference being had to the accompanying drawing, forming part thereof.

I claim:

The ornamental design for a flower support, as shown.

RUTH GERTH.
